UNITED STATES PATENT OFFICE

154,097

DESIGN FOR A NURSERY LAMP

Edward Brenner, Hollywood, Calif.

Application June 11, 1947, Serial No. 139,582

Term of patent 7 years

(Cl. D48—20)

To all whom it may concern:

Be it known that I, Edward Brenner, a citizen of the United States, residing at Hollywood, in the county of Los Angeles and State of California, have invented a new, original, and ornamental Design for a Nursery Lamp, of which the following is a specification, reference being had to the accompanying drawing, forming part thereof.

The figure is a perspective view of a nursery lamp, showing my new design.

The ornamentation shown on the front edge of the base is continued around the back, but otherwise the back portion of the lamp is plain.

I claim:

The ornamental design for a nursery lamp, as shown and described.

EDWARD BRENNER.
